Des. 218,473
Patented Aug. 18, 1970

218,473

PITCHER

Robert D. Asch, 74 Sunnyside Ave.,
Montreal, 217 Quebec, Canada

Filed June 3, 1969, Ser. No. 17,486

Claims priority, application Canada Apr. 16, 1969

Term of patent 7 years

Int. Cl. D7—01

U.S. Cl. D44—21

FIG. 4

FIG. 2

FIG. 1

FIG. 3

FIG. 5

FIG. 6

FIG. 10

FIG. 7

FIG. 8

FIG. 9

FIG. 1 is a side elevational view of a pitcher, showing my new design:

FIG. 2 is a front elevational view:

FIG. 3 is a rear elevational view:

FIG. 4 is a top plan view:

FIG. 5 is a bottom plan view;

FIG. 6 is a fragmentary sectional view on line 6—6 of FIG. 5;

FIG. 7 is a front elevational view of a pitcher showing another form of my new design;

FIG. 8 is a front elevational view thereof;

FIG. 9 is a rear elevational view, partly in section on the line 9—9 of FIG. 8; and

FIG. 10 is a top plan view.

I claim:

The ornamental design for a pitcher, as shown and described.
